[57] CLAIM

The ornamental design for a tire, as shown and described.

DESCRIPTION

FIG. 1 is a perspective view of a tire showing our new design, it being understood that the tread pattern is repeated throughout the circumference of the tire, the opposite side being substantially the same as that shown;

FIG. 2 is a front elevation view thereof;

FIG. 3 is a side elevation view thereof on a reduced scale; and

FIG. 4 is an enlarged, fragmentary front elevation view thereof.

FIG.1

FIG. 2

FIG.4

UNITED STATES PATENT AND TRADEMARK OFFICE
CERTIFICATE OF CORRECTION

PATENT NO. : Des. 313,776

DATED : January 15, 1991

INVENTOR(S) : William M. Hopkins et al.

It is certified that error appears in the above-identified patent and that said Letters Patent is hereby corrected as shown below:

On the title page, item [75] should read as follows:

Inventors: William M. Hopkins, Hudson; Robert A. Brightwell, Uniontown; Frederick W. Miller, Akron; Richard L. Galante, Akron; Terry J. Waibel, Wadsworth; and Michael A. Kolowski, Mogadore, all of Ohio

Signed and Sealed this

Thirtieth Day of June, 1992

Attest:

DOUGLAS B. COMER

Attesting Officer

Acting Commissioner of Patents and Trademarks
